SMOKE INDICATOR

Thomas W. McNeill and Frederic McNeill, Chicago, Ill.; said Frederic McNeill assignor to said Thomas W. McNeill

Application March 7, 1932, Serial No. 597,146

12 Claims. (CL 88—14)

This invention relates to indicating devices and more particularly to devices of this character for indicating the presence and density of smoke and the like.

5 One object of the present invention is to provide a simple and economical device for the purpose intended having a rigid and sturdy construction and capable of being installed with a minimum amount of time and effort.

10 Another object is to provide an efficient form of indicating device for smoke and the like which is in the form of a unitary construction and requires connection at one side only of a smoke conduit such as the breeching or other connection between a combustion chamber and smoke stack.

15 Another object of the invention is the provision of a unitary smoke indicating device equipped with means whereby samples of the products of combustion are effectively brought into position or area affording the maximum advantage for indicating the presence of smoke and for determining the relative density thereof.

20 Another object is to provide a convenient arrangement whereby the thickness of the body of smoke through which the light rays travel may be readily altered.

25 Still another object is the provision of means for visually checking and calibrating the indication obtained by the indicating means.

30 A further object of the invention is to provide means associated with the light inlet and sight tubes whereby the transparent panels closing the end of the tubes will be protected from deposits of smoke and soot thereon.

35 A further object is to provide means for promptly and effectively clearing the device of smoke so that the operator may be assured that he is obtaining a "zero" indication.

40 A still further object of the invention is to provide an arrangement for passing light rays through a body of smoke onto a light sensitive means whereby variations in the density of the smoke will produce variations in the condition of the light sensitive means due to the changes in 45 intensity of the light impinging upon it.

To these and other ends the invention resides in certain improvements and combinations of parts, all as will be hereinafter more fully described, the novel features being pointed out in the claims as the end of the specification.

In the drawings:

Fig. 1 is a front elevation of the device of the present invention;

55 Fig. 2 is a plan view;

Fig. 3 is a longitudinal section along line 3—3 of Fig. 2;

Fig. 4 is a fragmentary sectional plan view along line 4—4 of Fig. 3;

Fig. 5 is an enlarged sectional view of one of 5 the sight tubes, showing the ventilating apertures and the arrangement for securing the glass in the end of the tube;

Fig. 6 is a fragmentary sectional view of the tube taken substantially along lines 6—6 of Fig. 10 10 and showing the provision for horizontal adjustment of the tube;

Fig. 7 illustrates a modified construction of the smoke chamber; and

Fig. 8 is a modified view showing the adaptation of the invention for use with a light sensitive 15 indicating means.

Similar reference numerals throughout the several views indicate the same parts.

The present embodiment of the invention provides a smoke indicating and measuring device which is particularly advantageous for use in connection with smoke conduits which are inaccessible except from one side and thus it not only performs all of the functions of smoke indicating 25 devices heretofore in use, but at the same time materially reduces the size of equipment and the number of parts with a consequent reduction in cost both of materials and installation.

Referring more particularly to the drawings, 30 numeral 10 indicates generally the box or housing which constitutes the smoke trap chamber. In its preferred form the housing 10 is tapered but it is to be understood that the shape of the housing is in general immaterial. The housing 35 10 is preferably of metal either in sheet form or cast and is provided with a flange 11 having bolt holes 12, 12 formed therein as a convenient means for attaching the housing to a breeching or other conduit through which the products of combustion 40 are conveyed between the point of combustion of the fuel and the point of emission from the stack into the open air. For the sake of simplicity only one wall of the breeching or smoke conduit is shown and is indicated by numeral 13 45 in Fig. 2. The breeching or smoke conduit has an opening therein registering with the opening 14 of the housing 10.

Means are provided for causing a stream of 50 gases from the breeching to enter and pass through the smoke chamber formed by the housing 10. While this result may be effected in various manners, one expedient which has been found very satisfactory is to provide a deflecting plate 15 located in cooperative relation with the 55

mouth of the opening in the smoke chamber. This deflector is preferably, although not necessarily, secured on the housing by means of detachable securing devices, being in the present instance screws or bolts 16, 16 passing through the wall of the chamber and threaded into tapped openings in flanges 11, 17 formed on the deflector. The deflector 15 is preferably formed with a portion 18 extending in a direction substantially parallel with the axis of the opening 14, and comprises another portion 19 extending out of alignment with the portion 18 so as to be biased in a direction opposed to the travel of the smoke through the conduit. At this point it may be pointed out that the deflector 15 may be disposed as shown in Figs. 2 and 4 or may be reversed by merely inverting it and securing it in such position. Thus the device may be secured in an operative manner on either side of the conduit by merely inverting the deflector.

Assuming the deflector 15 to be in the position indicated in Fig. 2 and, with the smoke coming from the right, at least a portion of the smoke within the breeching will pass into the housing 10 on the near side of the deflector and pass out of the housing on the opposite side thereof. It is therefore apparent that the density of the smoke contained at any given moment in the chamber 10 will bear a substantially constant ratio to the condition of the entire body of smoke passing through the breeching.

Means are provided for continuously indicating the smoke content of the gases passing through the smoke chamber 10. In the present instance this means comprises an arrangement of parts adapted to convey to the eye of the attendant an indication by means of which he may be instantly informed concerning the relative density of the smoke passing through the smoke chamber. For this purpose a source of light is provided in the form of a lamp, the housing of which is indicated at 20, see Figs. 1 and 2. The light rays entering the opening 21, in the present instance, pass out of the chamber through a similar opening 22 in line with the opening 21 and located in the opposite wall of the housing 10. From the opening 22 the light rays from the lamp 20 are directed into a mirror 23 arranged to deflect the rays at an angle whereby the intensity of the light from the lamp may be observed without looking directly toward the lamp. One or more additional mirrors may be arranged for use in conjunction with the mirror 23 whereby it is possible to enable the attendant to view the light effects at any reasonable distance from the smoke trap chamber. If desired, however, the mirror arrangement may be dispensed with so that the attendant may view the lamp directly through the smoke chamber.

While varying forms of construction may be employed to substantially close the openings 21 and 22 in the housing 10, in the present instance each opening is preferably provided with an adjustable tube, these tubes being indicated at 24 and 25. For the purpose of slidably associating the tubes 24 and 25 with the housing 10, sleeves 26 and 27 are formed at the respective openings 21 and 22.

The tubes 24 and 25 are substantially alike and therefore further detailed description of one will suffice. Referring particularly to Figs. 2, 5 and 6, the tube 25 is provided at its end with a light transmitting panel 28 of glass or other suitable material held in place thereon by a ring 29 threaded interiorly to engage on a complementary

threaded part of the tube 25. Thus the glass may be removably secured on the end of the tube to permit the passage of light therethrough, but substantially closing the end of the tube from the entrance of air. For ordinary installations it has been found desirable to provide tube 25 with a translucent panel of ground or frosted glass or other suitable material and to fit the tube 24 with a transparent panel. Thus the light passing through the tube 25 to the mirror is diffused and softened, making for greater ease in observation. Furthermore, when no mirror is used, so that the attendant views the translucent panel directly, it is unnecessary for him to take a position exactly in front of the panel in order to obtain a reading of the condition of the interior of the smoke chamber.

In order to keep the panels 28 free from smoke, soot and the condensation of moisture thereon, one or more ventilated apertures 31 are provided in the tubes 24 and 25 which are controlled by an adjustable ring 32 having similar spaced apertures 33, 33 therein by means of which the apertures 31 may be opened or closed to a greater or less extent. The ring 32 may be formed similar to an ordinary hose clamp and is provided with extended portions through which a bolt 34 passes so that when the nut of the bolt is tightened thereon it will cause the ring to grip the tube with more or less friction so that the ring may be secured in any adjusted position. The purpose and function of the apertures 31 in the tubes 24 and 25 will be fully pointed out as the description proceeds.

The lamp 20 and the mirror 23 are preferably associated with the housing 10 so as to be carried thereby and thus form a unitary construction. For this purpose there is provided a bracket element 35 suitably secured to the under side of the housing 10 and bearing a laterally extending part or web 36 to which are attached the inner ends of a pair of carrying arms 37 and 38, see Fig. 1. The outer ends of the arms 37 and 38 are supported by means of braces 39 and 40, the inner ends of which are bolted at 41 to a downwardly extending web 42 on bracket 35. The lamp housing 20 is carried by a base 44 which is secured near the outer end of arm 37. An adjustable connection, indicated at 45, is provided between the housing 20 and the base 44 to permit the lamp to be tilted in such a manner that its rays will enter tube 24 to the best advantage. The mirror support, in a similar manner, is pivotally adjustable on a base member 46 secured to the outer end of arm 38.

A pair of auxiliary supports 47 and 48 are arranged upon the arms 37 and 38 and are provided with guide rings 49 and 50 in which the tubes 24 and 25 are slidably supported. Set screws 51 are threaded into the rings 49 and 50 and extend therethrough to bear against the surface of the tubes whereby the latter may be positively held in any adjusted position.

According to the description thus far, it is apparent that the light rays from the lamp 20 will pass through tube 24, into and through the smoke chamber and thence through tube 25 either direct to the attendant's eye or to his eye through the medium of the mirror 23.

The adjustability of the tubes 24 and 25 makes it possible to vary the distance over which the light rays will travel through the smoke in the smoke chamber. For practical purposes the tubes may be considered as relatively free from smoke or, at least, the smoke will pass only a short dis-

tance into the ends of the tubes. Thus by moving the ends of the tubes nearer together, the thickness of the smoke body through which the light rays pass is substantially decreased.

5 The purpose of the apertures 31 will now be more fully described. When the smoke chamber 10 is properly connected to the smoke conduit or breeching of a furnace, the breeching being connected to the ordinary smoke stack, there will be a certain negative pressure within the breeching caused by the natural flow of hot gases up the stack. This negative pressure will, of course, extend to the interior of the smoke chamber and will cause outside air to flow into the smoke chamber through apertures 31 when they are in open position. This inflow of air insures that the tubes 24 and 25 will at all times be clear of smoke, especially between the apertures and the closed end of the tube. Thus, no opportunity is afforded 20 for the smoke to approach the glass panel 28 with the consequent lessening of its transparency.

It has been found that, in tubes of relatively small diameters running from five or six inches on down to sizes considerably smaller, very effective results are obtained by spacing the air inlet apertures from the closed end of the tube a distance at least equal to or greater than the interior diameter of the tube. In this manner, a barrier of inflowing air is provided between the glass 30 panel and the smoke, and a relatively still body of air will be maintained in the tube adjacent the closed end thereof.

For the purpose of accurately regulating the inflow of air to operate under varying conditions 35 of smoke stack draft, it is desirable to equip standard units with a series of controlled apertures extending longitudinally of the tube. For this purpose one or more additional rings are provided as indicated at 32^a, such rings controlling two or more circumferentially spaced apertures similar to aperture 31.

An additional sight means, in the present instance, is provided for affording the attendant another view of the smoke sample illuminated by 45 the light rays. For this purpose a sleeve 52 is formed in the housing 10 and is arranged with its opening in line with the light rays passing across the chamber between the openings 21 and 22 so that the smoke illuminated by such light 50 rays may be viewed through this sleeve. An adjustable sight tube 53 is provided for the sleeve opening 52 and is adapted to be held in fixed position therein by means of a set screw 54. The end of tube 53 is closed by a glass panel 55 held 55 in place by a threaded ring 56 similar to the construction already described in connection with tube 25. The tube 53 is also preferably provided with one or more ventilating apertures adapted to be controlled by an adjustable ring 57 all as 60 previously described.

The arrangement just described provides another very important function, namely, to enable the attendant to quickly and thoroughly clear the entire smoke chamber. This is done by simply removing the ring 56 and glass panel 55 thus opening the entire tube 53 for the ingress of outside air. In lieu of merely removing the ring and glass, the entire tube 53 may be removed from opening 52. The immediate result of this operation, while smoke is being discharged through the breeching and up the stack, is to entirely displace all smoke in the trap chamber with clear outside air. The attendant may thus be assured, while viewing the light effect in the mirror 28 or 70 directly through tube 25, that he is receiving an

absolute "zero" or "no smoke" indication. By again closing the sight opening the attendant will again promptly receive a smoke indication if there is smoke actually present in the furnace gases. Thus it is clear that a convenient check 5 for zero reading is provided without in any manner adjusting or disturbing the combustion chamber conditions.

The modified form of the invention illustrated in Fig. 7 is intended for use when, for any reason, 10 it may be undesirable to use a positive deflecting means such as the deflecting plate 15; or it may be used to assist the operation of the deflecting plate in effectively introducing the furnace gases into the smoke chamber. In this form 15 of the invention a suction tube 60, communicating with a suitable suction producing means, not shown, such as a draft producing fan, is connected at its inner end to the housing of the smoke chamber 10^a by means of a sleeve connection 61 formed in the housing. In order to regulate the suction through the tube 60 to the proper amount for the best operation of the device, there is provided a damper valve 62. In other respects this modified form is constructed similar to the form of the invention first described.

It has been found desirable for certain installations to equip the indicating device with means by which an indication other than a mere light effect may be transmitted either electrically or mechanically to a position of maximum convenience to an attendant. For this purpose a light sensitive means or device, located in an open hood or casing 65 (see Fig. 8), is arranged to receive the rays of light passing from the smoke chamber through light tube 25^a. The particular form of light sensitive means to be used in this connection is immaterial insofar as the present invention is concerned. Any arrangement whereby variations in the intensity of the light impinging on the light sensitive means may be continuously converted or transposed into mechanical or electrical effects will serve the purpose. The casing 65 of the light sensitive means is preferably supported on a standard 46^a located on an arm 38^a all similar to the construction illustrated in Fig. 1. When the indicating device is equipped with light sensitive means the end of tube 25^a is preferably closed with a transparent panel instead of a translucent panel as previously stated.

The use and operation of the device will now be described.

When it is desired to attach the indicator assembly to a smoke conduit such as the breeching of the furnace, a suitable opening is formed in the breeching, the opening being preferably about equal in size and shape to the opening 14 in the chamber 10. When a deflecting means such as the deflector 15 is to be employed, it will next be secured with the portion 19 extending angularly from the housing in a direction opposite to that in which the furnace gases flow through the breeching, so that the gases will be caused to enter the smoke chamber as above described. The 65 housing 10 is next bolted in place with the opening 14 aligned with the opening in the breeching so as to form a substantially gas tight connection.

After the device has been attached to the 70 breeching and furnace gases conducted therethrough the lamp will be lighted to illuminate a portion of the interior of the smoke trap chamber thus making readily visible any smoke passing through the chamber. The presence of smoke 75

may be noted by looking directly into the tube 25 or by viewing the light passing from this tube through one or more mirrors. The illuminated smoke may also be viewed through tube 53 located 5 in the end of the trap chamber. As above stated, the attendant may readily compare the interior of the chamber when free of smoke with its appearance when smoke is passing through it by simply removing the panel closing the end of tube 10 53 thus permitting outside air to rush in due to the draft and clear the chamber or at least that portion normally illuminated by the lamp.

When it is desired to employ the light sensitive means 65 as a part of the indicating device, 15 all of the major adjustments will be ordinarily made before the device leaves the factory. After connection of the device to the breeching, certain additional slight adjustments may be necessary in order to adapt the device to the requirements 20 of the particular furnace installation. In making the final adjustments the operation of the indicating means, which is connected to the light sensitive cell, is carefully checked in conjunction with observations of the density of smoke passing 25 through the area lighted by the lamp 20. When the person installing the device is assured that no smoke is passing through the trap chamber, as by opening tube 53, he next observes the instruments which are associated with the light 30 sensitive cell, and if these instruments do not give a "zero", or "no smoke" indication, he makes the necessary adjustments so that such an indication will be given. For convenience in 35 making proper adjustments the base of the lamp 20 is preferably adapted for slidable movement toward and from the smoke chamber in suitable guides located on the arm 37; or the lamp itself may be mounted for horizontal adjustment within 40 its casing. Other adjustments may involve a modification of the instrumentalities combined with the light sensitive cell or may involve a change in the candle power of the lamp as by means of a variable resistance element connected 45 therewith or by merely substituting for the lamp another lamp of different brightness.

After checking the "zero" point, the device may next be observed with varying densities of smoke to check the indications made under such conditions. If the density of the smoke is not represented accurately by the indicating instruments 50 one expedient for correcting the indication is the adjustment of the tubes 24 and 25 to bring their ends at the proper distance from each other so that a body of smoke of the desired thickness may be obtained. The smoke will not enter the tubes 55 to any considerable extent by reason of the ventilating apertures therein, and, as these apertures are capable of variation, they too will, in some cases, be useful in the proper regulation of the thickness of the body of smoke through which the light rays pass. The ventilating openings 60 thus not only serve to keep the glass at the ends of the tubes from becoming dirty, but also assist, in some cases at least, in the proper regulation of the thickness of the smoke body. After the indicating devices have been properly calibrated 65 to suit the requirements of a particular job, they will require very little further attention. However, the operator may always confirm the indication given by the instruments by observing the amount of smoke in the smoke chamber through the sight tube 53.

The operation of the modified form, shown in 70 Fig. 7, is substantially the same as in the first

form with the exception that an additional adjustment is possible by varying the angle of the damper valve 62 or in any other way varying the suction at the inlet end of the tube 60.

From the foregoing description it is apparent 5 that the present invention provides a unitary device adapted for ready attachment to a smoke passage to afford an accurate indication of the smoke content of the gases traveling through the passage. As the gases are caused to travel 10 continuously through the device, it is possible to indicate accurately at any given instant the relative amount of smoke produced in the combustion chamber, and the instruments for effecting the indication can be brought into any convenient 15 position. Where an electrical indicating device is associated with the light sensitive means, the device obviously may be located in any position convenient to the attendants charged with the responsibility of maintaining the combustion 20 chamber in a smoke free condition. Dual instruments may also be provided at any other distant point. For example, at the station of an executive in charge of a battery of boilers. The device of the present invention can be made up in 25 standard form, but at the same time it is adapted for a nice adjustment to suit the requirements of a particular power plant. One very important advantage which the present invention affords is that it is not necessary to project the light rays 30 into or through the breeching proper. This consideration is of the utmost importance when the breeching is inaccessible except from one side. The device may be employed either with or without 35 a mechanical deflector, and when the deflector is used it may be easily arranged in the proper position to deflect gases into the smoke chamber regardless of direction of travel of the smoke. In installations where the deflecting means is not used it will be obvious that a portion of the smoke 40 and gases passing through the smoke conduit will naturally eddy or flow into and out of the smoke trap chamber and the density of the smoke therein will bear an approximately constant relation 45 to the density of the smoke in the main conduit.

While the present description sets forth a preferred embodiment of the invention, numerous changes may be made in the construction without departing from the spirit of the invention, and it is therefore desired that the present embodiment 50 be considered in all respects as illustrative and not restrictive, reference being had to the appended claims rather than to the foregoing description to indicate the scope of the invention.

We claim:

1. A smoke indicating device comprising a housing forming a chamber substantially closed except on one side, means for readily attaching the open side of said housing to a smoke conduit, 60 detachable deflecting means mounted on the housing and projecting into the interior of the conduit for causing at least a portion of the smoke from the smoke conduit to enter into and pass through said housing back into said conduit, and a transparent panel located in the wall of said housing through which the interior of the smoke chamber may be viewed.

2. A smoke indicating device comprising in combination a smoke conduit having an opening 70 therein extending laterally of the direction of the flow of smoke and gases therethrough, a box-like housing secured directly to said conduit and extending outwardly at substantially a right angle thereto, said housing having a single open- 75

ing in register with the opening in said conduit, means for causing a flow of at least a portion of the gases in said conduit into the housing and thence back into said conduit, and a transparent panel located in the outer end of said housing through which the interior of the housing may be viewed.

3. A smoke indicating device comprising in combination a smoke conduit having an opening in the side thereof, a housing forming a smoke chamber, secured to said conduit and having a single opening therein registering with the opening in said conduit, a deflecting plate located substantially centrally of said housing and having a portion thereof extending into the housing and another portion extending into the conduit and biased in a direction opposite the direction of travel of the smoke whereby said deflector will cause a stream of smoke to enter the housing at one side of its opening and leave the housing at the other side, and means associated with said smoke chamber for indicating the smoke content thereof.

4. A smoke indicating device comprising in combination, a smoke conduit having an opening therein extending laterally of the direction of the flow of gases therethrough, a unitary, substantially uniformly tapered housing forming a smoke chamber detachably secured directly to said conduit and having a single opening substantially as large of the greatest diameter of said chamber so as to facilitate the filling of the entire chamber with smoke, said opening registering with the opening in said smoke conduit, an auxiliary conduit connected to said chamber at a point remote from the opening into the smoke conduit, means for causing a suction through said auxiliary conduit whereby a deflection of the gases from said smoke conduit into said housing is effected, and means for indicating the relative concentration of smoke within the said chamber.

5. A smoke indicating device comprising a smoke conduit, a trap chamber associated therewith and adapted for the passage of smoke therethrough, a light inlet opening in said chamber comprising an adjustable tube mounted in a wall of the chamber and adapted to be extended thereto, a source of light arranged to direct light rays through said tube and into the chamber, a light sensitive means aligned with said tube and arranged to receive light rays from the source of light after such rays have passed through at least a portion of said chamber, and means whereby the distance of the inner end of the tube relative to the light sensitive means may be altered whereby the thickness of the body of smoke through which the light rays pass may be varied.

6. A smoke indicating device comprising a smoke conduit, a trap chamber associated therewith and adapted for the passage of smoke therethrough, a pair of spaced apart, aligned tubes extensible into the housing from opposite sides of said housing, a source of light arranged to direct light rays through one of said tubes into the chamber and through the other tube, means located at the remote end of said second tube adapted to be influenced by changes in the intensity of the light impinging upon it whereby the concentration of the smoke in the trap chamber may be indicated, and means whereby the spacing of the inner ends of said aligned tubes may be altered so as to vary the distance the light rays will pass through the chamber proper.

7. A smoke indicating device comprising a housing forming a smoke trap chamber adapted to be

connected to a smoke conduit to receive at least a portion of the smoke normally passing through the conduit, aligned light inlet and outlet tubes located in said housing, a bracket mounted directly on said housing and independent of said tubes, arms carried directly by said bracket and extending outwardly of the housing, a lamp carried by one of said arms and disposed to direct light rays through said aligned light inlet openings, and a light sensitive means carried by the other of said arms and adapted to receive light rays from the lamp after the rays have passed across the smoke chamber through said aligned openings.

8. In a smoke indicating device a tapering box-like housing forming substantially a closed chamber except at its large end which is provided with an opening substantially congruent with said end, means for readily attaching the open end of said housing directly to the side wall of a smoke conduit provided with a single opening registering with the opening in said housing whereby a portion of the smoke and gases passing through the conduit will enter said housing, and means associated with said housing for indicating the relative density of smoke within said housing.

9. A smoke indicating device comprising a housing forming a smoke trap chamber adapted to be connected to a smoke conduit to receive at least a portion of the smoke normally passing through the conduit, aligned light inlet and outlet openings in said housing, a bracket mounted directly on said housing, arms carried directly by said bracket and extending outwardly of the housing, a lamp carried by one of said arms and disposed to direct light rays through said aligned light inlet openings, a light sensitive means carried by the other of said arms and adapted to receive light rays from the lamp after the rays have passed across the smoke chamber through said aligned openings, adjustable tubes adapted to extend into the housing to vary the effective thickness of the smoke body therein, and auxiliary guiding means mounted on said arms and supporting said tubes for sliding movement.

10. A smoke indicating device comprising in combination, a smoke conduit having a single opening therein extending laterally of the direction of flow of gases therethrough, a box-like housing comprising interconnected sidewalls of tapered, tubular form and an end wall closing the small end of the housing, the large end of said housing having an opening substantially congruent with the interior of said housing and of such size as to substantially register with the opening in said conduit, means for readily attaching the large open end of said housing directly to the side wall of the smoke conduit with its opening in substantial registration with the opening in said conduit whereby a portion of the smoke and gases passing through the conduit will enter and fill substantially the entire chamber, and means associated with said housing for indicating the density of smoke therein.

11. A smoke indicating device comprising in combination, a smoke conduit having a single opening therein extending laterally of the direction of flow of gases therethrough, an elongated box-like housing having an opening at one end substantially congruent with the interior of said housing and of such size as to substantially register with the opening in said conduit, means for readily attaching the open end of said housing directly to the side wall of the smoke conduit with its opening in substantial registration

with the opening in the conduit, a deflecting plate located within the housing and extending into the interior of the smoke conduit whereby a portion of the smoke and gases passing through the conduit will enter and fill substantially the entire chamber and means associated with said housing for indicating the density of the smoke therein.

12. In a smoke indicating device the combination of a housing forming a chamber substan-

tially closed except on one side, means for readily attaching the open side of said housing to a smoke conduit, and deflecting means mounted on the housing and projecting into the interior of the conduit for causing at least a portion of the smoke from the smoke conduit to enter into and pass through said housing back into the conduit. 5

THOMAS W. McNEILL.
FREDERIC McNEILL.
